UNITED STATES PATENT OFFICE.

HUBERT SCOTT-PAINE, OF SOUTHAMPTON, ENGLAND.

TAIL-PLANE AND THE LIKE FOR AIRCRAFT.

1,375,421.

Specification of Letters Patent. Patented Apr. 19, 1921.

Application filed March 17, 1920. Serial No. 366,459.

To all whom it may concern:

Be it known that I, HUBERT SCOTT-PAINE, a subject of the King of England, residing at Southampton, in the county of 5 Hants, England, have invented certain new and useful Improvements in Tail-Planes and the like for Aircraft, of which the following is a specification.

The present invention relates to tail-10 planes and the like for aircraft, its object being to provide an improved construction of tail-plane and the like, that is to say of any plane which is situated to the rear of the main planes and may therefore be designated a trailing-plane.

Heretofore it has been customary to construct a trailing plane-structure with planes of neutral section and to obtain any lifting or depressing effect therefrom by giving 20 to the plane an appropriate tilt.

The present invention provides a multi-plane tail or other trailing plane-structure for aircraft having one or more of the planes formed with a lifting camber.

The present invention further provides a 25 tail unit or other trailing plane-structure for aircraft having one or more of the planes formed with a lifting camber and one or more with a reversed lifting camber, or in the case of a monoplane tail unit, the single plane may have a reversed lifting camber.

A further feature of this invention is the arrangement, in an aeroplane or other aircraft, of a multiplane tail or other multi-plane trailing plane-structure provided with one or more planes formed with a reversed lifting camber and so situated with relation to the propeller or airscrew that the 35 said plane or planes of reversed lifting camber are more strongly exposed to the slip-stream than the remaining plane or planes of the said structure.

This invention is of particular use in the 40 case of a tail-plane for craft of the flying boat type when leaving the water because the center of resistance is then at its lowest point (due to the hull resistance in the water) and the correction for the engine-thrust requires to be greatest. The invention 45 is of special value in craft having "pusher" engines but can also be used in those having tractor engines.

The accompanying drawing is a diagrammatic illustration of the application of this 55 invention to a flying-boat.

The hull of the boat is indicated at 10 with any usual or desired type of main-plane-structure at 11 and 12; the engine 13 with the airscrew 14 is mounted, as is usual 60 with flying boats, above the hull and between the main planes, the air-screw being either a tractor as shown in full lines or a "pusher" as shown in broken lines.

In this construction the tail unit is of 65 biplane formation, whereof the lower plane 20 has a lifting camber and the upper plane 21 has a reversed lifting camber, that is to say a lifting camber employed upside down so as normally to give a depression effect at 70 the after end of the vessel. The tail unit is situated at the rear of the propeller 14 and at such a level that the lower plane 20 is either partially screened by one of the main planes, or is otherwise so positioned 75 that it is less exposed to the slip-stream from the airscrew than the upper plane 21. The elevator control of the machine may be effected by the usual elevator planes 22 hinged to the rear edge of the tail planes 80 20, 21 and controlled in the ordinary manner by the pilot.

The employment of a bi-plane tail unit naturally tends to greater fore-and-aft stability of the machine but it will be seen that 85 since the plane 21 is more exposed to the slip-stream from the airscrew than the lower plane 20, it will tend automatically to correct the balance of the machine when the latter is disturbed by varying engine 90 thrust; an increase of the engine thrust tends to cause the machine to dive, but the effect of the increased slipstream on the upper plane 21 of the tail unit produces an increased downward thrust on the tail unit 95 thereby correcting or tending to correct the tendency of the machine to dive.

Various modifications may be made in the exact arrangement and disposition of the tail plane or planes, and the invention is not 100 restricted to the application of the hereinbefore described features to a tail unit, but includes their application to any trailing plane-structure, that is to say a trailing plane-structure having one or two or more operative planes.

What I claim as my invention and desire to secure by Letters Patent is:—

1. In an aircraft, a trailing plane-structure provided with a plane formed with a reversed lifting camber and so situated with relation to the airscrew that the said plane of reversed lifting camber is fully exposed to the slip-stream.
2. In an aircraft, a multiplane trailing

structure provided with a plurality of 10 planes, one of which is formed with a reversed lifting camber and so situated with relation to the airscrew that the said plane with reversed lifting camber is more strongly exposed to the slip-stream than the 15 remaining plane area of said structure.

In testimony whereof I affix my signature.

HUBERT SCOTT-PAINE.
